UNITED STATES PATENT OFFICE

ALBERT HARGRAVES, OF AKRON, OHIO

DESIGN FOR A TIRE

Application filed January 10, 1930. Serial No. 34,089. Term of patent 14 years.

To all whom it may concern:

Be it known that I, ALBERT HARGRAVES, a citizen of the United States, residing at 1223 North Howard St., Akron, in the county of Summit and State of Ohio, have invented a new, original, and ornamental Design for Tire, of which the following is a specification, reference being had to the accompanying drawings, forming a part thereof:

In the drawings:

Figure 1 is a perspective view looking upon

a section of a tire showing my new design; Figure 2 is a cross-sectional view thereof; Figure 3 is a plan view thereof; and Figure 4 is a side elevation thereof. The design of the sidewalls of applicant's tire is the same on both sides.

I claim:

The ornamental design for a tire as shown and described.

ALBERT HARGRAVES.
